Attorney.

UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE-FRAME.

1,359,253.

Specification of Letters Patent. Patented Nov. 16, 1920.

Application filed September 3, 1919. Serial No. 321,305.

To all whom it may concern:

Be it known that I, JACOB KAUFMANN, a citizen of the United States, residing at Philadelphia, in the county of Philadelphia and State of Pennsylvania, have invented certain new and useful Improvements in Heddle-Frames, of which the following is a specification.

My invention relates to heddle-frames for 10 looms, and it relates more particularly to improved means for strengthening and stiffening the top and bottom rails of the frame and for supporting the heddle bars intermediate their ends. 15 The principal object of my present invention is to provide an improved form of stay or brace for the top and bottom rails of the frame which will effectually prevent springing of the frames, and at the same time, will 20 firmly support the heddle bars intermediate their ends, thereby insuring freedom and easy play of the heddles on the heddle bars.

My invention contemplates a form of stay or brace which can be readily and easily 25 attached in and detached from the frame, and which is so constructed and arranged as to effectively function for its intended purpose, while at the same time permitting the proper arrangement of the heddles in the 30 frame. My present invention is particularly applicable to that type of heddle frames in which there are provided single heddle bars at the top and bottom of the frame.

The nature and characteristic features of 35 my invention will be more readily understood from the following description taken in connection with the accompanying drawings, forming part hereof, in which;

Figure 1 is a front elevation of a heddle 40 frame provided with a stay or brace embodying the main features of my present invention;

Fig. 2 is an enlarged fragmentary detail view, partly in elevation and partly in section, of a portion of the structure shown in 45 Fig. 1, illustrating the manner of connecting the stay rod to the top and bottom rails of the frame; and

Fig. 3 is a transverse section thereof, taken 50 on approximately the line 3-3 of Fig. 2, certain portions being shown in elevation.

Referring to the drawings, the heddle frame there shown comprises the top and bottom rails 5, usually made of wood, and connected at their respective ends by means 55 of the end strips 6. Extending from end to end of the heddle frame, and arranged near the top and bottom rails in the usual manner are the heddle bars 7, upon which the heddles 8 are mounted and supported. 60

The stay rod proper comprises a thin flat strip of metal suitably located in the heddle frame at desired places intermediate the ends thereof. Each end of the stay rod 9 is centrally slotted as at 10 to provide a recess 65 within which the heddle bar 7 is supported against sidewise displacement and also against displacement toward the center of the frame, so that when tension comes on the heddles as the shed is formed the heddle 70 bars 7 will be properly maintained in position.

The slot 10 at each end of the stay rod 9 is provided with an enlarged portion 11, which is engaged by a hook like extension 75 12 formed on the inner end of a bolt 13 which passes through the rail 5. The other end of the bolt 13 is threaded to receive a complementally threaded nut 14, preferably of the wing type. A washer 15 is arranged 80 on the bolt 13 on the outer side of the rail 5, and a split lock washer 16 is interposed between the washer 15 and the nut 16.

A metal plate 17 is suitably located on the inner edge of the rail 5, the bolt 13 85 passing therethrough. The plate 17 is provided with a slot 18 in which are positioned lugs or extensions 19 which are formed on the end of the stay rod or brace 9, one on each side of the slot 10. The purpose of 90 the foregoing arrangement is to positively position the ends of the stay rod 9 in the frame, and also to prevent spreading of the same when tension is applied by advancing the wing nut 14 on the bolt 13, as it will be 95 seen that otherwise the hook like extension 12 would tend to spread the bifurcated end of the stay rod 9.

It will be noted that with a device constructed and arranged as aforesaid, the stay 100 or brace 9 may be readily removed for the purpose of re-arranging the heddles mount-

ed on the bars 7, as may be required. In order to remove the stay or brace 9, it is only necessary to slack off the wing nuts 14 to allow the lugs 19 to be disengaged from the 5 slot 18 of the plate 17, which is carried on the inner edge of the rail 5, whereupon, the stay or brace 9 may be readily shifted with respect to said securing device, and, by reason of the slot 10 being open to the end of the stay rod 9, said stay rod may be readily 10 disengaged from the heddle bar 7 which is supported in said slot 10 thereof.

It will be seen that there is thus provided a simple and efficient form of stay or 15 brace, and means for securing the same intermediate the end of the heddle frame, which will effectively function to prevent springing of the top and bottom rails, which will also support the heddle bars and maintain 20 the same in proper positions, and which may be readily removed when desired, for the purpose of permitting the insertion or rearrangement of the heddles upon the heddle bars 7.

25 Having thus described the nature and characteristic features of my invention what I claim as new, and desire to secure by Letters Patent is:

1. In a heddle frame, top and bottom 30 rails, heddle supporting bars, a stay rod arranged intermediate the ends of the frame, said stay rod having slots at its ends in which the heddle bars are supported, means mounted in said top and bottom rails adapted to draw the ends of the stay rod toward the top and bottom rails, and members mounted on the inner edges of the top and bottom rails adapted to be engaged by the ends of the stay rod.

40 2. In a heddle frame, top and bottom rails, heddle supporting bars, a stay rod arranged intermediate the ends of the frame, said stay rod having slots at its ends in which the heddle bars are supported, means 45 mounted in said top and bottom rails adapted to draw the ends of the stay rod toward the top and bottom rails, plates mounted on the inner edges of the top and bottom rails having slots adapted to be engaged by the 50 ends of the stay rod to thereby position said stay rod and to prevent spreading of the ends thereof when tension is applied thereto.

3. In a heddle frame, top and bottom 55 rails, heddle supporting bars, a stay rod arranged intermediate the ends of the frame, said stay rod having slots at its ends in which the heddle bars are supported, means mounted in said top and bottom rails adapted to draw the ends of the stay rod toward the 60 said top and bottom rails, and plates mounted on the inner edges of the top and bottom rails having slots adapted to be engaged by the ends of the stay rod, said stay rod hav-

ing lugs on the ends adapted to engage said 65 slots in said plates to thereby position said stay rod and to prevent spreading of the ends thereof when tension is applied thereto.

4. In a heddle frame, top and bottom 70 rails, heddle supporting bars, a stay rod arranged intermediate the ends of the frame, said stay rod having slots at its ends in which the heddle bars are supported, and bolts mounted in the top and bottom rails having hook like extensions engaging enlarged 75 portions of said slots, said bolts having means adapted to cause said bolts to draw the ends of the stay rod toward the top and bottom rails.

5. In a heddle frame, top and bottom 80 rails, heddle supporting bars, a stay rod arranged intermediate the ends of the frame, said stay rod having slots at its ends in which the heddle bars are supported, and bolts mounted in the top and bottom rails 85 having hook like extensions engaging enlarged portions of said slots, said bolts having nuts on their outer ends adapted to cause said bolts to draw the ends of the stay rod toward the top and bottom rails.

6. In a heddle frame, top and bottom rails, heddle supporting bars, a stay rod arranged intermediate the ends of the frame, said stay rod having slots at its ends in which the heddle bars are supported, bolts 95 mounted in the top and bottom rails having hook like extensions engaging enlarged portions of said slots, said bolts having nuts on their outer end adapted to cause said bolts to draw the ends of the stay rod toward the 100 top and bottom rails, and members mounted on the inner edges of the top and bottom rails adapted to be engaged by the ends of the stay rod.

7. In a heddle frame, top and bottom 105 rails, heddle supporting bars, a stay rod arranged intermediate the ends of the frame, said stay rod having slots at its ends in which the heddle bars are supported, bolts mounted in the top and bottom rails having 110 hook like extensions engaging enlarged portions of said slots, said bolts having nuts on their outer ends adapted to cause said bolts to draw the ends of the stay rod toward the top and bottom rails, plates mounted 115 on the inner edges of the top and bottom rails having slots adapted to be engaged by the ends of the stay rod, when tension is applied by means of said bolts.

8. In a heddle frame, top and bottom 120 rails, heddle supporting bars, a stay rod arranged intermediate the ends of the frame, said stay rod having slots at its ends in which the heddle bars are supported, bolts mounted in the top and bottom rails having 125 hook like extensions engaging enlarged portions of said slots, said bolts having nuts on their outer ends adapted to cause said

bolts to draw the ends of the stay rod toward the top and bottom rails, and plates mounted on the inner edges of the top and bottom rails having slots adapted to be engaged by the ends of the stay rod, said stay rod having lugs on the ends adapted to engage said slots in said plates to thereby position

said stay rod and to prevent spreading of the ends thereof when tension is applied by means of said bolts.

10

In testimony whereof, I have hereunto signed my name.

JACOB KAUFMANN.
